UNITED STATES PATENT OFFICE.

THOMAS HOLMES, OF CHELSEA, MICHIGAN.

NUT-CRACKER.

SPECIFICATION forming part of Letters Patent No. 425,428, dated April 15, 1890.

Application filed August 31, 1889. Serial No. 322,610. (No model.)

To all whom it may concern:

Be it known that I, THOMAS HOLMES, a citizen of the United States, residing at Chelsea, in the county of Washtenaw and State of Michigan, have invented a new and useful Nut-Cracker, of which the following is a specification.

The invention relates to improvements in nut-crackers.

10 The object of the present invention is to provide a nut-cracker of simple and inexpensive construction capable of exerting great force, sufficient to crack the hardest nut without liability of smashing the nut too much for use.

15 The invention consists in the construction and novel combination and arrangement of parts, hereinafter fully described, illustrated in the accompanying drawings, and pointed out in the claims hereto appended.

20 In the drawings, Figure 1 is a perspective view of a nut-cracker constructed in accordance with the invention. Fig. 2 is a side elevation, a portion being broken away to show the construction of the lower end of the operating-lever.

25 Referring to the accompanying drawings, A designates the base of the machine, which is designed to be secured to a table or other suitable stand by screws or the like, which pass through perforations a in enlarged corners or feet a' of the base A. At the ends of the base A are upward-extending ears a^2 and a^3 , between which are pivoted an operating-lever B and a cracker-arm C.

35 The operating-lever is provided at its lower end opposite the pivotal point with a curved recess b , which receives the pointed free end c' of the cracker-arm C, and when the lever is raised the lower portion of the recess b engages the end c' and raises the cracker-arm, and when the operating-lever B is lowered the upper wall of the recess engages the end c' and forces the cracker-arm downward to within a short distance of the base, an ap-

40 proximately pyramidal projection D being provided to prevent the cracker-arm descending too far and to preserve a nut from too much compression. By this arrangement a pressure sufficient to crack the hardest shell

45 is brought upon a nut.

The opposing faces of the cracker-arm C

and the base are provided with serrations a and c^2 , which prevent the nut slipping, and the cracker-arm is also slightly curved, and when it is resting upon the projection D a 55 triangular opening is formed between it and the base, which will accommodate various-sized nuts and permits the amount of compression to be regulated.

The extreme lower end of the operating-lever B is provided with a shoulder b' , which engages with the base A and prevents the lever being raised too much, and the cracker-arm C is sufficiently long to project between the ears a^2 when depressed to prevent the 65 said arm turning to one side under extreme pressure.

From the foregoing description and the accompanying drawings the construction, operation, and advantages of the invention will 70 readily be understood.

What I claim is—

1. In a nut-cracker, the combination of the base, the cracker-arm pivoted to one end of the base and being slightly curved throughout its entire length and adapted to form an approximately triangular opening between it and the base when its free end rests upon the latter, and the operating-lever pivoted to the other end of said base and adapted to engage 75 the free end of the cracker-arm, substantially as described.

2. In a nut-cracker, the combination of the base, the cracker-arm pivoted to one end thereof, and the operating-lever pivoted to the other 85 end of the base and provided with a recess to receive the free end of the cracker-arm, substantially as described.

3. In a nut-cracker, the combination of the base, the cracker-arm pivoted to one end thereof, the operating-lever pivoted to the other end of said base, and the projection limiting the downward movement of the cracker-arm, substantially as described.

4. The combination of the base provided at 95 its ends with ears, the cracker-arm pivoted between the ears at one end of the base, the operating-lever pivoted between the ears at the other end of the base and provided with a curved recess to receive the free end of the 100 cracker-arm, and a projection to limit the free end of said arm, substantially as described.

5. The combination of the base provided with the ears a^2 and a^3 , the cracker-arm pivoted between the ears a^3 and having its free end projecting between the ears a^2 , the operating-lever pivoted between the ears a^2 and provided with a curved recess, and a shoulder to limit its upward movement, and the projection, substantially as described.

In testimony that I claim the foregoing as my own I have hereto affixed my signature in presence of two witnesses.

THOMAS HOLMES.
